[57] CLAIM

The ornamental design for amusement game, as shown and described.

DESCRIPTION

FIG. 1 is a perspective view of an amusement game showing my new design;

FIG. 2 is a left side elevational view thereof; the right side elevational view being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

The broken line showing of a game projectile is for illustrative purpose only and forms no part of the claim.

FIG. 3

FIG. 4

FIG. 5

FIG. 6
